UNITED STATES PATENT OFFICE.

ALONZO ALDRICH, OF BELOIT, WISCONSIN.

MACHINE FOR TRIMMING AND SLITTING PAPER.

No. 828,250.

Specification of Letters Patent.

Patented June 12, 1906.

Application filed August 10, 1904. Serial No. 220,234.

To all whom it may concern:

Be it known that I, ALONZO ALDRICH, a citizen of the United States, residing at Beloit, in the county of Rock and State of Wisconsin, have invented certain new and useful Improvements in Machines for Slitting and Trimming Paper, of which the following is a specification.

The present invention relates to that class of machines that are used for trimming paper to different widths, and more particularly to that subclass of machines that are provided with two sets of slitters or trimmers so arranged that when one set is working the other set is idle and accessible for the purpose of laterally adjusting its paired slitters relatively to each other, so as to be in readiness to be moved into working position as soon as needed for trimming a different width, the set previously working being by the same operation moved out of working position. Machines of this type are well known in the art. As heretofore constructed the paired slitters of each set move together and in the same direction in being moved into and out of working position, and since the co-operating slitters of each pair must when working be upon opposite sides of the paper it follows that one slitter of each pair is moved across the plane which the paper occupies while being slit or trimmed. This necessitates breaking the paper each time the one set is to be moved into and the other out of working position.

The principal object of the present invention is to provide a machine of such construction that the paper need not be broken in order to make this change from one width to another, and other objects are to otherwise improve the construction of machines of this class. In order to accomplish these objects, I use two sets of slitters, each of which sets comprises two (or more) pairs of co-operating slitters so arranged that when working the co-operating slitters of each pair are upon opposite sides of the paper, as is customary, and I provide means for moving the co-operating slitters of each set toward and from each other and toward and from the plane of the paper, so that none of the slitters crosses said plane in moving into or out of working position. In addition to this the slitters of the two sets are so connected that as one set is moving into working position the other set is moving out of working position, so that

there is no loss of either time or paper in changing the machine.

I believe myself to be the first to provide a slitting and trimming machine of such construction that it is not necessary to break the paper in changing from one width to another, or, in other words, a machine in which the co-operating slitters are moved toward and from each other without moving either across the plane of the paper, and I therefore desire it to be understood that the invention is not limited to mechanism of any particular construction for so moving them. Their movement in opposite directions being suggested, many different mechanisms for moving them and also for making the action of the two sets reciprocal will readily suggest themselves, and while I have illustrated the invention under three different modifications there are others that are within its scope.

In the accompanying drawings, which are made a part of this specification, Figure 1 is a side elevation of a machine embodying the invention in its preferred form. Fig. 2 is a plan view thereof. Fig. 3 is a vertical transverse section thereof on the line 3 3, Fig. 1. Fig. 4 is a detail of the gearing. Fig. 5 is a detail of the means for laterally separating the paired slitters. Figs. 6 and 7 are elevations of modifications.

The frame 1 may be of any desired construction so long as it meets the requirements of the machine. It has brackets 2 and 3 supporting two rolls of paper 4 and 5, standards 6, supporting a foot-board 7, adjustable standards 8, supporting one of the guard-boards 9, means for supporting the driving-shaft 11, and standards 12, supporting the other guard-board 13 and other parts hereinafter described.

As before stated, there are two sets of slitters, and each of these sets (as shown in the drawings) consists of two pairs of slitters, and the two slitters 14 and 15 of each pair are arranged in operative relation to each other. The lower slitters 14 of each set are carried by a shaft 16, upon which they are laterally adjustable relatively to each other (the term "laterally" being herein used with respect to the machine) in customary manner, and the shafts 16 of the two sets are journaled in boxes 17, carried at the opposite extremities of a pair of arms 18, which are mounted to rock or oscillate upon stub-shafts 19, supported by the standards 12. The

shafts 16 project beyond the boxes 17 at one end, and their projecting portions carry gear-wheels 20, that are adapted to mesh alternately with a pinion 21, carried by the driving-shaft 11, the parts being so proportioned and arranged that when the rock-arms are tilted in one direction one of the gear-wheels 20 will be in mesh with the pinion 21 and the other out of mesh, and when the rock-arms are tilted in the opposite direction these conditions will be reversed. The gear-wheels 20 are also adapted to mesh with corresponding gear-wheels 22 on the projecting ends of shafts 23, which carry the upper slitters 15 of the two sets. These shafts are mounted to both revolve and move endwise in bearings carried at the extremities of arms 24, that are mounted to rock or oscillate on stub-shafts 25, supported by the standards 12. The upper slitters of both sets are laterally adjustable upon their shafts, but are incapable of turning thereon. They are held in contact with the faces of the slitters 14 by coiled springs 26, each of which bears in one direction against one of the slitters and in the other direction against one of a corresponding number of collars 27, that are adjustably secured to the shafts, the movement of the slitters under the influence of the springs being limited by collars 28, adjustably secured to the shafts.

In addition to being laterally adjustable relatively to each other the upper slitters of each set are laterally movable together by reason of the endwise movability of the shaft carrying them. One end of the shaft has a reduced portion 29, which is surrounded by a sleeve 30, one end of which abuts against the shoulder resulting from the reduction of the shaft and the other end of which abuts against a collar 31, secured to the reduced portion of the shaft, so that the shaft is free to turn in the sleeve, but is incapable of endwise movement therein. The sleeve is provided with a rigid radial arm or handle 32, by which it may be partially rotated, and it is provided also with a spirally-disposed slot 33, into which projects a stud or pin 34, carried at the box 35 of the arm 24. This sleeve in fact forms the bearing in which the shaft revolves, and when the sleeve is turned in its bearing the slot 33 will act as a cam and coöperating with the fixed pin or stud 34 will move the shaft 23 endwise, carrying the slitters with it for a purpose hereinafter described.

For the purpose of rocking the arms 18 and 24 in opposite directions, and thereby moving the coöperating slitters of one set toward each other and into working positions and at the same time moving the coöperating slitters of the other set apart and into position to permit of their being adjusted, links 36 have their upper ends jointed to the arms, respectively, and their lower ends jointed to a partial disk or sector or equivalent device 37, secured to the shaft 38 of a hand-wheel

39. In mechanical effect the device 37 is the equivalent of two radial arms, and the links are connected to it at such points that as it is carried around by the shaft the links are moved endwise in different directions. 70

In Figs. 1 to 4 the coöperating slitters of the set nearest the rolls of paper, and herein-after called the "first" set, are in working positions, and the slitters of the other set, herein-after called the "second" set, are separated. While the second set is out of working position, the pairs of slitters composing it may be adjusted laterally to any desired distance apart. This is done by adjusting the lower slitters exactly to the positions they 80 are to occupy when at work and adjusting the upper slitters to a corresponding distance apart, but at such positions on their shaft that when the shaft is in normal position (with respect to its endwise movement) they 85 will lie in the vertical planes of the lower slitters, as shown in Figs. 2 and 3. If the handle 32 is then thrown to the position indicated by dotted lines in Fig. 1, the shaft will be moved endwise (toward the left-hand 90 side of Fig. 3) and the slitters 15 of the second set will be moved to the positions indicated by dotted lines in Fig. 2. This is to permit their peripheries to pass the lower slitters when the hand-wheel 39 is turned in 95 the proper direction to move them toward each other, and after this is done the shaft is moved endwise in the reverse direction by restoring the handle 32 to the position shown by full lines, and this movement brings the 100 flat faces of the upper slitters to bear against the flat faces of the lower slitters and puts the springs 26 under the proper tension. To this latter end the parts are so adjusted that the slitters come together before the endwise 105 movement of the shaft is completed, thus leaving a slight clearance between the hubs of the slitters 15 and the collars 28, as shown in Figs. 2 and 3 with respect to the first set. When the work to be done by the first set is 110 completed and the second set has been adjusted as just described, the lever 32 of the first set is moved, so as to move the shaft endwise and separate the flat faces of the coöperating slitters of the first set. The hand-wheel 39 is then turned in the proper direction and the arms 18 and 24 thereby rocked, 115 so as to move the slitters of the first set apart and move the slitters of the second set toward each other, so that their peripheries slightly 120 pass the plane of the paper. The lever 32 of the second set is then thrown in the proper direction to move the shaft endwise and bring the flat faces of the coöperating slitters into contact, as already described, and the 125 slitters of the first set in position to be adjusted.

In Fig. 6 the rock-arms 18 and 24 are secured to shafts 40 and 41, that turn in bear- 130

ings in the standards 12 and are located at such distance apart that when either set is in working position the rock-arms are vertical and the shafts carry gear-wheels 42, meshing 5 with a pinion 43 on the shaft of a hand-wheel 44. Otherwise the parts may be substantially as already described. Furthermore, any other suitable means may be used for moving the arms 18 and 24.

10 In Fig. 7 the shafts 16 and 23 are journaled in bearings carried by slides 45, that are mounted on vertical guides 46 on the standards 12, so that they are capable of vertical movement thereon. Any suitable means 15 may be used for moving the slides, so that the slitters of one set are moved toward each other while the slitters of the other set are moved apart. In the drawings I have shown the slides as being jointed to the upper ends 20 of links 47, (one for each slide,) the lower ends of which are jointed to a part 48, similar to the part 37, already described, so that when the shaft carrying said part is turned one set of links will be moved upward, there- 25 by moving upward the upper slitters of the first set and the lower slitters of the second set, and the other set of links will at the same time be moved downward, thereby moving downward the lower slitters of the first set 30 and the upper slitters of the second set. For holding the slitters in operative relation to each other any desired mechanism may be used. In the drawings I have shown a notched wheel 48, secured to the shaft 38, a bolt 49, adapted to enter one or the other of 35 said notches, a spring 50 for holding the bolt normally in engagement, and a treadle or foot-piece 51 for retracting it.

What I claim as new, and desire to secure 40 by Letters Patent, is—

1. In a slitting and trimming machine, the combination of two sets of slitters adapted for use alternately, each set comprising a plurality of pairs of slitters, the slitters of each 45 pair being located upon opposite sides of the plane of the paper and movable toward and from said plane and toward and from each other, means for driving the slitters, means for laterally adjusting the pairs of slitters relatively to each other, and means for moving the paired slitters in opposite directions, toward and from said plane and toward and from each other, substantially as described.

2. In a slitting and trimming machine, the 55 combination of two sets of slitters comprising a plurality of pairs of coöperating slitters, the coöperating slitters of each pair being located upon opposite sides of the plane of the paper and movable toward and from each other, means for driving the slitters and means for moving the slitters of each set in opposite directions as aforesaid, substantially as described.

3. In a slitting and trimming machine, the 60 combination of two sets of slitters comprising

a plurality of pairs of coöperating slitters, the coöperating slitters of each pair being located upon opposite sides of the plane of the paper and movable toward and from said plane and toward and from each other, and means common to both sets of slitters for simultaneously moving the slitters of each set in opposite directions, and corresponding slitters of the two sets in opposite directions, thereby moving one set into and the other 75 set out of working position, substantially as described.

4. In a slitting and trimming machine, the combination of two sets of slitters comprising a plurality of pairs of coöperating slitters, the 80 coöperating slitters of each pair being located upon opposite sides of the plane of the paper and movable toward and from said plane and toward and from each other, and means for simultaneously moving corresponding slitters of the two sets in opposite directions, thereby bringing one set into and the other 85 set out of working position, substantially as described.

5. In a slitting and trimming machine, the 90 combination of two sets of slitters adapted for use alternately, each set comprising a plurality of pairs of slitters, the coöperating slitters of each pair being located upon opposite sides of the plane of the paper and movable 95 toward and from said plane and toward and from each other, means including rock-arms carrying the slitters and means for rocking the arms to simultaneously move the slitters of each pair in opposite directions toward 100 and from said plane and toward and from each other, substantially as described.

6. In a slitting and trimming machine, the combination of two sets of slitters adapted for use alternately, each set having a plurality 105 of slitters located on opposite sides of the plane of the paper, means for driving the slitters, means for moving all of the slitters of one set that are located on one side of said plane toward and from said plane, and means for moving all of the slitters of the other set that are located on one side of said plane toward and from said plane, substantially as 110 described.

7. In a slitting and trimming machine, the 115 combination of two sets of slitters adapted for use alternately, each set having a plurality of slitters located on opposite sides of the plane of the paper, means for moving all of the slitters of one set that are located on one side of said plane toward said plane, and means for simultaneously moving all of the slitters of the other set that are located on one side of said plane away from said plane, and vice versa, substantially as described.

8. In a slitting and trimming machine, the 120 combination of two sets of slitters adapted for use alternately, each set having a plurality of slitters located on opposite sides of the plane of the paper, means for moving all of 125

the slitters of one set that are located on one side of said plane toward said plane, and means for simultaneously moving all of the slitters of the other set that are located on the aforesaid side of said plane away from said plane, and vice versa, substantially as described.

9. In a slitting and trimming machine, the combination of two sets of slitters adapted for use alternately, each set having a plurality of slitters located upon opposite sides of the plane of the paper, means for driving the slitters and means including rock-arms for moving the slitters of each set in opposite directions toward and from said plane, substantially as described.

10. In a slitting and trimming machine, the

combination of a set of slitters arranged in pairs the slitters of each pair being located upon opposite sides of the plane of the paper and movable in opposite directions toward and from said plane and toward and from each other, means for laterally adjusting the pairs relatively to each other, means for simultaneously moving the slitters in opposite directions toward and from said plane, and means for simultaneously moving similar slitters laterally and in the same direction, substantially as described.

ALONZO ALDRICH.
